PRODUCTION OF GASOLINE BY CATALYTIC CRACKING

Elmon L. Claridge, Houston, Tex., assignor to Shell Development Company, New York, N. Y., a corporation of Delaware

Application November 19, 1956, Serial No. 623,256

3 Claims. (Cl. 208—94)

This invention relates to the production of gasoline from petroleum residues through catalytic cracking.

Although other methods are sometimes employed, the general practice in producing gasoline from petroleum residues through catalytic cracking involves separation of a suitable catalytic cracking feed stock from the petroleum residue by a flashing operation. In this operation, the petroleum residue is heated in a suitable coil in a furnace to a flashing temperature which is generally on the order of 750—950° F. and the heated and partially vaporized residue is then passed to a flashing chamber in which the pressure is lower than that prevailing in the heating coil. The pressure in the flashing chamber may be up to about 50 p. s. i. g. but is usually maintained below atmospheric pressure by a suitable source of vacuum. The pressure may be as low as 10—20 mm. Hg. In some cases, two stages of flashing are applied with the first stage being under a slight super-atmospheric pressure, e. g. 40 p. s. i. g., with the second flashing stage under vacuum, e. g. 100 mm. Hg., either with or without heating between the flashing stages. Under these conditions and especially when the pressure is below atmospheric, the vapor velocities in the flashing zone are quite high and the residence time is quite low. As a consequence, there is considerable tendency for the flashed vapors to entrain part of the residue. Even traces of entrained residue exert a very detrimental effect on the quality of the overhead product as catalytic cracking feed stock. Also, the petroleum residue normally contains appreciable amounts of organo-metallic compounds which tend to pass overhead with the flashed product and these two are extremely detrimental even in very small concentrations.

In order to reduce the carryover of residue and reduce somewhat the concentration of organo-metallic compounds (which are of low volatility), it has been the practice in some cases to pass the flashed vapors through a relatively inefficient rectification zone to which part of the condensed flashed product is supplied as knock-back or reflux. Usually only from 3 to 10 trays are provided. An efficient rectification cannot be applied here since the pressure drop required for such rectification would be prohibitive and the temperatures are in the range where the increased residence time required for efficient rectification would lead to undesired thermal reactions and coking.

The bottoms from the flashing operation may be further flashed as described but are generally withdrawn as a product of the process and sent to thermal cracking, asphalt manufacture, Bunker C fuel oil, or the like, depending upon the particular situation at hand. The reflux from the rectification zone is sometimes recycled to the furnace but is normally combined with the flasher bottoms and are hence withdrawn. This reflux stream contains the tarry material which, except for the reflux stream, would be entrained in the flasher overhead product.

2

The flasher overhead product after being cooled to condense normally liquid hydrocarbons is passed as the feed stock to the catalytic cracking unit.

In the catalytic cracking unit, the said oil is cracked in the vapor phase at temperatures upward of 850° F. to about 1050° F. with a suitable solid cracking catalyst. The catalytic cracking step is effected in the conventional manner which is well known and therefore requires no detailed description. The vapors from the catalytic cracking reactor consist of normally gaseous materials as well as gasoline, gas oil and partially converted and unconverted feed oil, and therefore boil over the whole temperature range up to about 1000° F. This material, containing for example 30% gasoline, is passed to a fractionation zone and enters the fractionation zone at a temperature which is close to that in the catalytic cracking reactor, i. e., it is vastly superheated. It is introduced into the fractionation zone near the bottom below a gas oil drawoff tray. In this bottom section there is little or no rectification. In order to effect efficient fractionation of the oil vapors from the catalytic cracking unit into the desired products in the upper portion of the fractionation column, a part of the bottom product from the fractionator is withdrawn, cooled, and reintroduced into the fractionation column at a point in the bottom section above the feed inlet point but below the said gas oil drawoff tray. A large amount of this oil is recycled in this way to effect a sufficient desuperheating of the feed entering the fractionation section of the fractionating column. The net make of this oil is removed as bottom product from the fractionation column.

The vapors passing from the catalytic cracking reactor to the fractionator normally carry small though appreciable amounts of catalyst fines and these fines collect in the bottom product of the fractionator. Thus, this bottom product is usually called slurry oil. This slurry oil is of exceptionally poor quality as a catalytic cracking feed stock. It is a heavy, highly aromatic and highly refractory oil which, when included in catalytic cracking feed stock, greatly increases the coke make. It is therefore normally withdrawn from the system and either thermally cracked, used as a cutter stock in producing Bunker C fuel oil, or used for the production of carbon black. In some cases, however, it contains considerable amounts of cracking catalyst, and in order to recover this catalyst the oil is returned to the catalytic cracking unit in spite of its poor quality. In these cases, however, the slurry oil is settled to produce a thickened slurry thereby allowing return of the catalyst with a minimum recycle of the oil vehicle to the catalytic cracking unit. The relatively catalyst-free oil from such thickening operation, generally called clarified oil, is withdrawn as a product and used as mentioned above.

The process of the present invention follows in broad outline the above described operations. However, in the process of the invention, better use is made of the slurry oil, thickened slurry and/or clarified oil while at the same time improving the feed stock to the catalytic cracking unit.

In spite of the fact that the slurry oil is an exceptionally poor catalytic cracking feed stock, it contains valuable feed stock components. These are concentrated in the front end of the oil. This is due to the fact that in the application of the slurry oil as a means for de-superheating the cracked vapors fed to the fractionator, this slurry oil receives practically no rectification. Consequently it boils over a very wide range (in spite of its high temperature origin in the fractionating column) and generally has a quite low Engler initial boiling point,

e. g. 450° F. On the other hand, at the temperatures normally encountered in the rectification section of the flashing operation, e. g. 600-800° F., the cracking catalyst is capable of acting favorably on the removal of coke forming constituents in the catalytic cracking feed.

In the process of my invention, the net make of the slurry oil or a part of it at an adjusted temperature (depending upon the volume) is used as a knockback in the rectification section of the flasher used for the catalytic cracking feed stock preparation whereby the desirable catalytic cracking feed stock components in the slurry oil are vaporized by the catalytic cracking feed stock vapors in this section and are thus returned to the catalytic cracking unit. In the preferred embodiment of the invention, the catalytic cracking feed stock is improved by contact with the cracking catalyst in this same section in which case two advantageous results are realized.

The improved process of the present invention will be described as to its details in the following in which reference will be made to a specific preferred embodiment illustrated in the flow diagram which constitutes the accompanying drawing. In this flow diagram, the few apparatus indicated are illustrated diagrammatically.

Referring to the drawing, reduced crude, i. e., crude petroleum which has been topped to remove lower boiling straight-run material, is passed by line 1 to the coils 2 in a suitable heater 3 wherein it is heated to an outlet temperature of about 800° F. The heated and partially vaporized reduced crude is then passed by the transfer line 4 to the vacuum flasher vessel 5 in which the pressure is maintained at about 70 mm. Hg. The material enters the flash chamber tangentially so that the centrifugal action of the swirling vapors tends to throw out the major part of the suspended residue droplets. The residue, which in this case is pitch, is withdrawn from the flash chamber by line 6.

The flashed vapors pass through the overflow of the flash chamber to the bottom section of the rectifier 7. Rectifier 7 is provided in this case with four grid trays. Bubble trays may not be used since they would be clogged with catalyst. Shower decks may be used, but are less efficient than grid trays. A stream of liquid oil containing finely divided catalyst in suspension is introduced into the upper portion of the rectifier 7. This material passes downward through the rectification zone countercurrent to the rising vapors from the flasher. The vapors entering the rectification zone in this case are at a temperature of about 710° F. and in appreciably superheated condition. They are in relatively large amount compared to the amount of slurry oil introduced. For example, in the particular case, the ratio of these two materials introduced is about 10:1.

The overhead vapors from the rectifier 7 are cooled in condenser 8 and passed to separator 9. The vapors are drawn off to the vacuum source via line 10, and the liquid condensate, called flashed distillate, is passed to the catalytic cracking unit 11.

In a typical case, the flashed distillate is cracked in the catalytic cracking unit at a temperature of 950° F. to a 55% conversion. The vapors from the catalytic cracking reactor are passed via line 12 to the bottom section of fractionator 13. These vapors carry some catalyst fines in suspension. The catalyst collects in the heavy oil at the bottom of the fractionator and is withdrawn in suspension with the oil. A large amount of this bottom oil, i. e., slurry oil, is withdrawn and recycled by line 14 after cooling in cooler 15 in order to desuperheat the hydrocarbon feed entering the upper portion of the fractionator. The net make of slurry oil is passed by line 16 to the top of rectifier 7 as described.

In two typical cases, the vapors entering the rectifier 7 have the following Engler distillations shown in columns A and B:

TABLE 1
Vacuum engler distillation corrected to atmospheric pressure, ° F.

The slurry oil in two typical cases has the distillation shown in columns C and D in the above table. The slurry oil removed from the bottom of the rectifier 7 has, in two typical cases, the distillation shown in columns E and F in the above table.

It will be seen that a sizable amount of the front end of the slurry oil is vaporized and removed with the flashed vapors. It is generally desirable to remove only this portion of the front end of the slurry oil since, if the 25 flashing and rectification are carried out under conditions to cut deeply into the slurry oil, the quality of the catalytic cracking feed stock is impaired. Generally, the amount volatilized should not be more than 50% of the slurry oil introduced. The amount of the slurry oil removed in 30 the rectification step is regulated by regulating the amount and temperature of the slurry oil supplied to the rectification zone as described. If the net make of slurry oil is excessive, the excess is removed by line 17. If the net make of slurry oil is insufficient, the slurry oil may 35 be recycled. Thus, in the case illustrated, the feed to the flasher is 30,700 bbl./day. The flashed distillate vapors passing to the rectifier 7 amounts to 24,420 bbl./day. The net make of slurry oil in the fractionator 13 is 1,110 bbl./day. The net make of slurry oil withdrawn from the system by line 18 is 880 bbl./day. This net make of slurry oil from the fractionator 13 is insufficient for the optimum result. Therefore, the slurry oil withdrawn from the rectifier 7 by line 19 is passed to a thickener 20. A thickened slurry is withdrawn from the thickener by line 21 and recycled to the rectifier 7 in an amount of 45 1,800 bbl./day, which, with the slurry oil from the fractionator, gives a ratio of flashed distillate to slurry oil in the rectifier 7 of about 10.5. It will be appreciated that in order to maintain the system in balance, the slurry oil removed by line 18 as net make will contain the same 50 amount of catalyst as that withdrawn from fractionator 13.

The temperature of the slurry oil leaving the bottom of fractionator 13 is normally between about 600-700° F., and in the particular case it is about 687° F. If this slurry oil were passed to the rectifier 7 at this temperature, more than 50% of the slurry oil would be vaporized and combined with the flashed distillate. The slurry oil is therefore generally cooled somewhat, e. g., to 350-550° F. by the cooler 22 in line 16. In some cases, this cooler 60 may be eliminated by making use of the cooler 15. Thus, instead of removing net slurry oil make as shown, it may be removed from the stream in line 14 which has been cooled in cooler 15.

The improvement in the quality of the catalytic cracking feed stock due to contacting it with the cracking catalyst in the rectifier 7 increases as the concentration of catalyst in the slurry in this section is increased. It is not essential that advantage be taken of this additional 65 improvement. Thus, clarified oil, rather than slurry oil, can be used in the rectifier 7 while still retaining the former advantage. The slurry oil passed from the fractionator 13 normally contains from small amounts up to about 3 lbs. of cracking catalyst per barrel. This concentration may be increased in the rectifier 7 by initial

thickening of the slurry oil (not shown) or preferably by recycling thickened slurry as illustrated and described above. The concentration of cracking catalyst should, however, be limited such that the concentration in the slurry in line 19 does not exceed about 30 lbs./bbl. Additional cracking catalyst or clay may be added by line 23 if desired.

The effect of the suspended cracking catalyst on the quality of the resulting flashed distillate is illustrated in the following table wherein the properties of flashed distillates produced with and without suspended cracking catalyst in the rectification section are given. The concentration of cracking catalyst in the slurry was in this case 20 lbs./bbl.

TABLE 2

Pressure mm. Hg	Without Catalyst	With Catalyst
Feed Rate, lbs./hr.	398	416
Flashed Distillate, lbs./hr.	269	282
Knockback Oil, lbs./hr.	60	60

Ramsbottom Carbon Residue, Percent	0.290	0.128
Pitch Entrainment, Percent	2.72	0.72

The invention is not limited to the specific embodiment illustrated and just described. For instance, while the use of slurry oil thickened as to its catalyst content affords best results as regards improvement in the quality of the catalytic cracking feed stock, beneficial results may be obtained without such thickening, i. e., using the net slurry oil from the catalytic cracking fractionator without thickening. In some cases this may be even more advantageous since the concentration of desirable catalytic cracking feed components in the slurry feed to the rectification zone is higher. Additional knockback may be made up by the conventional method of supplying overhead product condensate to the rectification zone.

If desired, clarified oil rather than slurry oil may be used. This removes the improvement in the feed stock quality due to contact with the catalyst in the slurry oil, but still leaves the advantage of recovering as catalytic cracking feed in a simple and economical manner the most desirable feed stock components of the oil. If desired, other finely divided solids which may be more active in removing undesirable catalytic cracking feed stock components may be added to the oil to the rectification section either to replace the cracking catalyst missing in the clarified oil or to augment the cracking catalyst in the slurry oil. In any case, the cracking catalyst or other material passed to the rectification section in the flashing operation is withdrawn from the system and not recycled to the catalytic cracking unit where, due to the extremely bad effects of the heavier portion of the carrier oil, the advantages of the invention would be erased.

I claim as my invention:

1. In the production of gasoline from petroleum residues by catalytic cracking, the improved process which comprises in combination the steps of heating petroleum residue to flashing temperature, flashing the heated petroleum residue in a zone of reduced pressure thereby liberating flashed petroleum vapors, passing said vapors up through a rectification zone in countercurrent contact with a slurry of finely divided cracking catalyst in liquid oil produced as hereinafter specified, withdrawing a slurry from said rectification zone as a product of the process, condensing the vapors after said contact in a separate condensing zone, catalytically cracking the resulting condensate, passing the vapors from the catalytic cracking at essentially the cracking temperature to a fractionation zone at an inlet thereto, withdrawing slurry oil from the bottom of said fractionation zone, cooling a first part of said withdrawn slurry oil and returning said cooled first part back to said fractionation zone at a point above said inlet thereby to desuperheat the catalytically cracked vapor feed entering said fractionation zone, and passing another part of said withdrawn slurry oil to the above said rectification zone to provide said slurry of finely divided cracking catalyst in liquid oil whereby the vapors of the catalytic cracking feed are contacted with the catalyst in the slurry oil prior to removing the latter from the system in said product of the process and at the same time hydrocarbons in the slurry oil which are present due to the use of a slurry oil to effect desuperheating are vaporized by the said vapors of the catalytic cracking feed in said rectification zone and passed with said feed to the catalytic cracking zone.
2. Process according to claim 1 further characterized in that said slurry withdrawn from said rectification zone as a product of the process is passed to a partial settling zone and a part of said slurry more concentrated in finely divided catalyst is recycled from said partial settling zone to the top of said rectification zone to increase the concentration of finely divided cracking catalyst in suspension in the liquid oil in said rectification zone.

3. Process according to claim 1 further characterized in that the slurry oil passed to said rectification zone constitutes the total net make of said slurry oil in said fractionation zone and said slurry oil after being withdrawn from said fractionation zone is cooled to a temperature such that the slurry oil removed from said rectification zone as a product of the process is at least 50% of the net slurry oil introduced into said rectification zone.
